CURTAIN ROD

Oscar N. Whitehead, Wallingford, Conn., assignor
to H. L. Judd Company, Wallingford, Conn., a
corporation of Delaware

Application April 10, 1948, Serial No. 20,190

2 Claims. (Cl. 211—105.3)

1

My invention relates to curtain rods and in particular to improved means in a curtain rod for facilitating the operation of threading a curtain onto the rod.

It is an object of the invention to provide an improved device of the character indicated.

It is another object to provide an improved curtain-rod threading means that may present only smoothly rounded surfaces to the parts of the curtain that are being threaded and which may therefore facilitate the threading operation.

It is a further object to meet the above objects with a simple and relatively inexpensive construction that may nevertheless be sufficiently well reinforced to perform its intended functions in spite of considerable abuse.

Other objects and various further features of novelty and invention will be pointed out or will occur to those skilled in the art from a reading of the following specification in conjunction with the accompanying drawings. In said drawings, which show, for illustrative purposes only, a preferred form of the invention:

Fig. 1 is a fragmentary, partly broken-away, front view of an assembled telescopic curtain rod incorporating features of the invention;

Fig. 2 is a perspective view from the rear of the inner element or section of the rod of Fig. 1;

Fig. 3 is a front view of the end of the element of Fig. 2;

Fig. 4 is an end view of the element of Fig. 2;

Fig. 5 is a side view of the end of the element of Fig. 3; and

Fig. 6 is a flat layout of sheet material, suitable for use in fabricating the element of Fig. 2.

Briefly stated, my invention contemplates an improved end construction for a curtain rod, whereby only rounded and hence non-fouling surfaces may be presented to a curtain as the curtain is being threaded onto the rod. The invention has particular usefulness in connection with telescoping curtain rods, and in the form to be described, the end construction is adapted to the inner element of a two-element telescoping curtain rod.

Referring to the drawings, my invention is shown in application to a telescoping curtain rod comprising an outer element or rod section 10 and an inner element or rod section 11. Both elements 10—11 are generally flat rods of usual generally C-shaped section and may include flat front faces (12, for rod element 10, and 13, for rod element 11). In the outer element 10 reinforcement is obtained from flanges 14 which may be generally rounded and include rear por-

2

tions 15 more or less in the plane of a rear face. The flanges 14 may thus provide a generally C-shaped channel for suitably guiding and supporting the inner rod element 11. The general construction of the inner rod element 11 may be similar to that of the outer rod element 10, and is shown to include generally rounded flanges 16 more or less tangent to the front face 13. If desired, further reinforcement may be provided for the flanges 16 by folding over and crimping the exposed edges thereof, as shown at 17 in Fig. 2.

In accordance with the invention, I provide a means for so finishing the telescoping end 15 of the inner rod element 11 that it may be readily threaded, without snagging, into a curtain. Referring particularly to Fig. 6, it will be seen that in a preferred form I so cut away the forward end of the front face 13 that the flanges 16, or at least the material used in the rounded part of the flanges 16, may project forward of the front face, as at the tabs 18. To facilitate the necessary bending operation, I prefer that the outer edges 18' of the tabs 18 be cut away from the reinforcement edges 17, so that there need be no bending of the reinforced edge 17. The projecting tabs 18 may be bent around substantially to meet each other and, in a preferred form, to provide a smoothly rounded front contour for the element 11. Not only are the tabs 18 preferably bent around to meet each other, but they are also preferably bent to conform with the same general curvature as that of the flanges 16. When so bent, the nose or threading end of the element 11 may present a completely rounded and smooth surface, as will be clear.

To avoid all possibility of snagging a curtain, I prefer that the end or cut-away part of the front face of the threading element 11 project forward, as at 19, and that it be of generally rounded contour. Suitably formed, the projecting part 19 of the front face 13 may be abutting or at least adjacent the rounded flanges 18, as well as being substantially tangent thereto, and the threading end may be part of a smooth surface of revolution about a normal axis, as indicated generally at 20.

It will be appreciated that I have described an ingenious threading construction for particular application to the inner of two telescoping elements of a curtain rod. The construction is such as to provide inherently for its own reinforcement and to present smooth tangential 55 transitions from straight or flat surfaces to

curved surfaces wherever such transitions occur.

While I have described my invention in detail for the preferred form shown, it will be understood that modifications may be made within the scope of the invention as defined in the appended claims.

I claim:

1. In a thimble-ended sheet-metal C-shaped curtain-rod section, a substantially flat front face and spaced-off rounded and inwardly directed reinforcing flanges extending to form a rear face, the flanges at the thimble end of the section including such parts of said flanges as extend substantially to the point of tangency with said front face and extending longitudinally beyond said front face and being bent in a smooth curve to meet each other forward of said front face.

2. A curtain-rod section according to claim 1, in which the end of said front face is of generally

rounded contour so that when said flanges are bent to meet each other they are substantially adjacent said front face end throughout and substantially tangent to said front face end throughout.

OSCAR N. WHITEHEAD.
